UNIVERSALLY UNITED SCOOP FOR
SEPARABLE FASTENERS

Louis H. Morin, Bronx, N. Y.

Application November 21, 1944, Serial No. 564,487

12 Claims. (Cl. 24—205.13)

1

This invention relates to separable fasteners employing stringers having scoops to couple and uncouple the same. More particularly, the invention deals with what I term coreless double acting scoops so constructed as to provide universal coupling of the stringers. Still more particularly, the invention deals with scoops wherein pairs of male and female couplings are arranged on each surface of the scoop, and the coupling portions of one surface being opposed to the coupling portions of the other surface. The novel features of the invention will be best understood from the following descriptions when taken together with the accompanying drawing in which certain embodiments of the invention are disclosed, and in which the separate parts are designated by suitable reference characters in each of the views, and in which:

Fig. 1 is a perspective view showing one scoop on the beaded edge of a fastener stringer.

Fig. 2 is a reduced side view of the scoop as seen in Fig. 1.

Fig. 3 is a section substantially on the line 3—3 of Fig. 2.

Fig. 4 is a section substantially on the line 4—4 of Fig. 2.

Fig. 5 is a view similar to Fig. 1, showing another form of scoop.

Fig. 6 is a reduced side view of the scoop shown in Fig. 5.

Figs. 7 and 8 are sections substantially on the lines 7—7 and 8—8 of Fig. 6.

Fig. 9 is a view similar to Figs. 1 and 5, showing another form of scoop.

Fig. 10 is a reduced side view of the scoop shown in Fig. 9; and

Figs. 11 and 12 are sections substantially on the lines 11—11 and 12—12 of Fig. 10.

My present invention deals with scoops of separable fastener stringers of what I term the coreless type. By this is meant, the scoops are formed from die castings without the use of core pins or the like on the parting line of the dies, thus adapting scoops of this type and kind for casting in multiple directly upon the stringer tape. In other words, the scoops are of such form as to readily free themselves from the die cavities in the separation of the dies, and at the same time, the scoops are so formed as to provide male and female couplings retaining the scoops of coupled stringers against transverse and lateral separation.

On the other hand, the scoops are also of what I term the double action type. That is to say, both side portions of the scoops are substantially

2

the same, thus sliders are adaptable for movement along the stringers with the narrow end of the sliders arranged in either of two directions on the stringers in coupling and uncoupling the scoops.

Notwithstanding the fact that the male and female couplings have a staggered arrangement on each surface of the scoop, the arrangement on opposed surfaces is such that stringers may be united in a universal manner, that is to say, with the ends of the stringers arranged in any position one with respect to the other. This latter construction materially simplifies installation of the stringers in the supports therefor by manufacturers, and avoids any possibility of improper mating arrangement of stringers in the supports. At the same time, production of the stringers is simplified in that a single stringer is produced. In other words, no lefts and rights are required.

20 In Figs. 1 to 4 inclusive is shown one form of scoop construction, the scoop being generally identified by the reference character 15. In Figs. 1 and 2, 16 represents part of a stringer tape, and 17 the beaded edge thereof. The scoop 15 comprises a mounting end portion 18 arranged upon the beaded edge 17 and a coupling end portion 19 which projects outwardly from said beaded edge.

The coupling end portion of the scoop 15 has an outer coupling end or head 20 which is substantially of diamond shape cross sectional form. 30 The head 20 forms the male coupling of the scoop which is adapted to enter the channeled or recessed portion of adjacent scoops in coupling stringers together, the channel or recess being indicated by the reference character 21 in Figs. 1 and 2 of the drawing, and this recess is arranged on both surfaces of the scoop, and each recess is substantially V-shaped in cross sectional form, as will clearly appear from a consideration of Fig. 1.

40 The walls of the head 20 and recesses 21 taper in the direction of the side surfaces of the scoop in order to provide clearances between adjacent coupled scoops for bending and flexure of the stringers. These tapers are indicated in Fig. 1 of the drawing and are more clearly illustrated by the reduced lines of the head 20, as seen at 22 in Fig. 2 and the reduced lines 23 at the inner portions of the recesses 21. In other words, the scoops are of greatest thickness along the longitudinal center lines represented at 24 in Fig. 1 of the drawing, and this also appears from the cross sections through the scoop shown in Figs. 3 and 4.

45 The center line 24 divides the scoop into coupling side portions 25 and 26, note Figs. 1 and 3.

3

The head 20 on the coupling side portion 25 is of greater height than at the coupling side portion 26 to form on the line 24 between these side portions a coupling shoulder 27 on the upper surface of the scoop. The coupling side portion 26 extends downwardly a greater distance than the coupling side portion 25 of the head to form a corresponding coupling shoulder 28 on the lower surface of the scoop. This construction is clearly shown in Fig. 3 of the drawing.

In Fig. 4 of the drawing is shown a section through the recessed portion of the scoop. At this portion, the coupling side 26 is of greater height than the coupling side 25 to form a coupling shoulder 29 on the upper surface of the scoop, whereas the coupling side 25 extends downwardly a greater distance than the coupling side 26 to form a coupling shoulder 30 with the lower surface of the scoop.

As will clearly appear in Fig. 2 of the drawing, the bevelled surfaces forming one side of the head 20 and one side of the recesses 21 register in a single ridge 31 at upper and lower surfaces of the scoop and extending substantially from the peaks of the head to the base of the recesses. In other words, the shoulders 27 and 28 terminate substantially at the high-points of the diamond head 20, whereas the shoulders 29 and 30 terminate at the base of the recesses or channels 21.

When scoops of opposed stringers are coupled together, it will be apparent that the shoulder 27 of one scoop will engage the shoulder 30 of an adjacent scoop, and the shoulder 28 of said scoop will engage the shoulder 29 of still another scoop in coupling the scoops against transverse separation. From this standpoint, it may be said that the outer end portions of the heads 20 have interengaging male coupling shoulders 27 and 28, whereas the inner end portion of the recesses or channels 21 have male coupling shoulders 29 and 30, and that the intervening portion of the scoops, in other words, the outer ends of the recesses or channels and the inner ends of the head have flat abutting and uncoupled surfaces, except to the extent that the shoulders extend onto said surfaces.

It will also appear that opposite side surfaces of the scoop body 15 have recesses 32 in alignment with the base of the recesses or channels 21, and these are provided to facilitate greater tilting or swinging movement of the scoops one upon the other in the flexure or bending thereof.

In Figs. 5 to 8 inclusive is shown a modified form of scoop 33, and as this scoop is generally of the same contour as the one already described (the head 34 corresponding to the head 20 and the channels or recesses 35 corresponding to the channels or recesses 21) no further specific description with regard to this structure of the scoop will be given, as it simply would be a repetition.

The structure of Figs. 5 to 8 inclusive differs from the structure in Figs. 1 to 4 inclusive, in providing on the center high-point line 36 of the scoops limited coupling shoulders 37 and 38 at the upper and lower peaks of the head 34 and other limited coupling shoulders 39 and 40 at the base of the channels or recesses 35. In other words, the shoulders 37 and 38 are similar to the shoulders 27 and 28, and the shoulders 39 and 40 are similar to the shoulders 29 and 30, except that they are located centrally of the heads and recesses rather than being disposed on one wall only of the heads and recesses.

4

Omitting for the sake of consideration the part of the shoulders 39 and 40, which extend onto the walls of the head 34 and recesses 35, it may be said that the shoulders occupy only part of the outer portions of the head and only part of the inner portions of the recesses, and these parts would form a limited coupling engagement between adjacent scoops. However, as shown in the accompanying drawings, the shoulders extend onto the head and from this standpoint would constitute a further modification in adding the interengaging couplings on the head where they are substantially entirely lacking on the ridges 31.

Considering the cross sectional view in Fig. 7 of the drawing, it will appear that the shoulders 37 and 38 are formed by what may be termed notches or recesses 42 and 43 in the head 34. In considering Fig. 8 of the drawing, it will appear that the shoulders 39 and 40 are formed by what may be termed enlargements or projections 44 and 45 in the recesses 35. In connection with the cross sectional views shown in Figs. 3, 4, 7, 8, as well as 11 and 12, it will be apparent that for the purpose of simplifying the illustrations these views simply show the part of the scoop where the section line is indicated in the associated figures, omitting the background.

In Figs. 9 to 12 inclusive is shown another modified form of scoop 46. Here again the general scoop structure is much the same as that shown in Figs. 1 to 4 inclusive as well as in Figs. 5 to 8 inclusive, and again no further detailed description with regard to the scoop structure will be given. The scoop 46 has shouldered couplings 47-48 and 49-50, quite similar to the shoulders 37 and 38, formed in the head 51 of the scoop, whereas the shoulders 49 and 50 are formed in the channel or recesses 52. The primary difference between the two structures shown in Figs. 5 to 8 and 9 to 12 is in the fact that the shoulders 47 and 48 are formed by channels 53 and 54, which are more or less conical in form or U-shaped in cross sectional form adapted to receive core like projections 55 and 56. So formed, these channels and projections in and of themselves provide for interlocking the scoops against lateral or pull-apart separation, in addition to the interlocking against transverse separation afforded by the shoulders or faces 47-50.

Having fully described my invention, what I claim as new and desire to secure by Letters Patent is:

1. A scoop for separable fastener stringers comprising a coupling head at one end of the scoop of substantial diamond cross sectional form producing on upper and lower surfaces of the scoop transversely arranged projections, the scoop inwardly of said projections having transverse recesses of V-shaped cross sectional form adapted to receive the projections of scoops of a companion stringer in retaining coupled stringers against lateral separation, the projecting portions of said head having centrally thereof oppositely faced coupling shoulders on upper and lower surfaces thereof, the recessed portions of the scoop having centrally thereof oppositely exposed coupling shoulders on opposed surfaces of the scoop, the last named shoulders being faced oppositely to said first named shoulders on each surface of the scoop, and said shoulders providing interengagement between coupled scoops of opposed stringers in retaining the scoops against transverse separation.

2. A scoop for separable fastener stringers comprising a coupling head at one end of the scoop of substantial diamond cross sectional form producing on upper and lower surfaces of the scoop transversely arranged projections, the scoop inwardly of said projections having transverse recesses of V-shaped cross sectional form adapted to receive the projections of scoops of a companion stringer in retaining coupled stringers against lateral separation, the projecting portions of said head having centrally thereof oppositely faced coupling shoulders on upper and lower surfaces thereof, the recessed portions of the scoop having centrally thereof oppositely exposed coupling shoulders on opposed surfaces of the scoop, the last named shoulders being faced oppositely to said first named shoulders on each surface of the scoop, said shoulders providing interengagement between coupled scoops of opposed stringers in retaining the scoops against transverse separation, and the coupling shoulders on said head being arranged from the longitudinal central portion of the head to the outer surface of the head.

3. A scoop for separable fastener stringers comprising a coupling head at one end of the scoop of substantial diamond cross sectional form producing on upper and lower surfaces of the scoop transversely arranged projections, the scoop inwardly of said projections having transverse recesses of V-shaped cross sectional form adapted to receive the projections of scoops of a companion stringer in retaining coupled stringers against lateral separation, the projecting portions of said head having centrally thereof oppositely faced coupling shoulders on upper and lower surfaces thereof, the recessed portions of the scoop having centrally thereof oppositely exposed coupling shoulders on opposed surfaces of the scoop, the last named shoulders being faced oppositely to said first named shoulders on each surface of the scoop, said shoulders providing interengagement between coupled scoops of opposed stringers in retaining the scoops against transverse separation, the coupling shoulders on said head being arranged from the longitudinal central portion of the head to the outer surface of the head, and the coupling shoulders of the recessed portion of the scoop being arranged along the inner wall of said recesses.

4. A scoop for separable fastener stringers comprising a coupling head at one end of the scoop of substantial diamond cross sectional form producing on upper and lower surfaces of the scoop transversely arranged projections, the scoop inwardly of said projections having transverse recesses of V-shaped cross sectional form adapted to receive the projections of scoops of a companion stringer in retaining coupled stringers against lateral separation, the projecting portions of said head having centrally thereof oppositely faced coupling shoulders on upper and lower surfaces thereof, the recessed portions of the scoop having centrally thereof oppositely exposed coupling shoulders on opposed surfaces of the scoop, the last named shoulders being faced oppositely to said first named shoulders on each surface of the scoop, said shoulders providing interengagement between coupled scoops of opposed stringers in retaining the scoops against transverse separation, and said shoulders being arranged centrally of the high-point of the projections of said head and centrally of the low-point of said recesses.

5. A scoop for separable fastener stringers comprising a coupling head at one end of the scoop of substantial diamond cross sectional form producing on upper and lower surfaces of the scoop transversely arranged projections, the scoop inwardly of said projections having transverse recesses of V-shaped cross sectional form adapted to receive the projections of scoops of a companion stringer in retaining coupled stringers against lateral separation, the projecting portions of said head having centrally thereof oppositely faced coupling shoulders on upper and lower surfaces thereof, the recessed portions of the scoop having centrally thereof oppositely exposed coupling shoulders on opposed surfaces of the scoop, the last named shoulders being faced oppositely to said first named shoulders on each surface of the scoop, said shoulders providing interengagement between coupled scoops of opposed stringers in retaining the scoops against transverse separation, said shoulders being arranged centrally of the high-point of the projections of said head and centrally of the low-point of said recesses, the coupling shoulders of the recessed portions of the scoops being formed by projections of the scoop body extending into said recesses, and the enlargements of said head being recessed adjacent the coupling shoulders to receive said last named projections.

6. A scoop for separable fastener stringers, said scoop comprising mounting and coupling ends, the coupling end having on upper and lower surfaces oppositely converging outer and inner walls throughout the width thereof defining substantially V-shaped transverse projections at the outer portion of said coupling end and outer walls of transverse recesses, said surfaces having inwardly diverging walls defining the inner walls of said transverse recesses, said recesses and projections providing interlocking engagement between coupled stringers preventing lateral separation of the stringers, said outer converging walls of the projections having oppositely faced coupling shoulders centrally of said scoop, the inner walls of said recesses having oppositely faced coupling shoulders, the coupling shoulders of one surface of the scoop being faced opposite to the same coupling shoulders on the other surface of said scoop, and all of the converging walls of said scoop converging from the central portion of the scoop to side surfaces thereof.

7. A scoop for separable fastener stringers, said scoop comprising mounting and coupling ends, the coupling end having on upper and lower surfaces oppositely converging outer and inner walls throughout the width thereof defining substantially V-shaped transverse projections at the outer portion of said coupling end and outer walls of transverse recesses, said surfaces having inwardly diverging walls defining the inner walls of said transverse recesses, said recesses and projections providing interlocking engagement between coupled stringers preventing lateral separation of the stringers, said outer converging walls of the projections having oppositely faced coupling shoulders centrally of said scoop, the inner walls of said recesses having oppositely faced coupling shoulders, the coupling shoulders of one surface of the scoop being faced opposite to the same coupling shoulders on the other surface of said scoop, all of the converging walls of said scoop converging from the central portion of the scoop to side surfaces thereof, and said side surfaces of the scoop having notches in alignment with the

transverse recesses on opposed surfaces of the scoop.

8. A scoop for separable fastener stringers, said scoop comprising mounting and coupling ends, the coupling end having on upper and lower surfaces oppositely converging outer and inner walls converging from the central portion of the scoop to side surfaces and throughout the width thereof and defining substantially V-shaped transverse projections at the outer portion of said coupling end and outer walls of transverse recesses, said surfaces having inwardly diverging walls defining the inner walls of said transverse recesses, said recesses and projections providing interlocking engagement between coupled stringers preventing lateral separation of the stringers, one side of the upper surface of the outer wall of said scoop being extended to form centrally of the scoop a coupling shoulder, the opposite side of the lower surface of said wall of the scoop being extended to form centrally of the scoop a coupling shoulder, the inner wall of the recesses of said scoop being extended on said surfaces at sides opposed to said first named extensions to form centrally of the scoop coupling shoulders faced in a direction opposite to said first named shoulders, and said shoulders providing universal coupling of scoops of opposed stringers retaining coupled stringers against transverse separation.

9. A scoop for separable fastener stringers, said scoop comprising mounting and coupling ends, the coupling end having on upper and lower surfaces oppositely converging outer and inner walls throughout the width thereof defining substantially V-shaped transverse projections at the outer portion of said coupling end and outer walls of transverse recesses, said surfaces having inwardly diverging walls defining the inner walls of said transverse recesses, said recesses and projections providing interlocking engagement between coupled stringers preventing lateral separation of the stringers, one side of the upper surface of the outer wall of said scoop being extended to form centrally of the scoop a coupling shoulder, the opposite side of the lower surface of said wall of the scoop being extended to form centrally of the scoop a coupling shoulder, the inner wall of the recesses of said scoop being extended on said surfaces at sides opposed to said first named extensions to form centrally of the scoop coupling shoulders faced in a direction opposite to said first named shoulders, said shoulders providing universal coupling of scoops of opposed stringers retaining coupled stringers against transverse separation, and the side portions of the coupling

end of the scoop having walls converging from the central portion thereof to side surfaces of the scoop.

10. A scoop for separable fastener stringers, said scoop having a mounting end portion and a coupling end portion, the coupling end portion comprising a head and a recessed portion each defined at least in part by upper and lower walls, said recessed portion having oppositely faced shoulders, said head having on upper and lower walls thereof oppositely faced shoulders, and said head having widthwise of the scoop intersecting upper walls and intersecting lower walls.

11. A coreless scoop for separable fastener stringers, said scoop having mounting and coupling end portions, the coupling end portion being divided centrally and longitudinally into coupling halves each having upper and lower walls which define ridges and channels, said upper and lower ridges and channels converging outwardly in the direction of the side edges of the scoop, upper and lower sides of the coupling end portions of the scoop having centrally thereof longitudinally spaced coupling shoulders, the shoulders on one side being faced in directions opposite to each other and arranged diametrically opposite to the shoulders of the other side, said coupling shoulders providing inter-engagement between coupled stringers to prevent transverse separation of the stringers, and said first named ridges and channels retaining said coupled stringers against lateral separation.

12. A scoop for separable fastener stringers, said scoop having a mounting end portion and a coupling end portion, the coupling end portion comprising a head and a recessed portion each defined at least in part by upper and lower walls, said recessed portion having oppositely faced shoulders, said head having on upper and lower walls thereof oppositely faced shoulders, said head shoulders being spaced, lengthwise of the scoop, both from the free end of the head and from the deepest part of the recessed portion.
